DUST PREVENTIVE COMPOSITION

Edward R. Butcher, Harmarville, Pa., assignor to
Gulf Research & Development Company, Pittsburgh, Pa., a corporation of Delaware

No Drawing. Application October 14, 1944,
Serial No. 558,728

4 Claims. (Cl. 252—88)

The present invention relates to dust preventive compositions, and it is particularly concerned with an improved liquid spraying agent adapted to inhibit the surface dusting of the soil in playgrounds, training camps, dirt walks and the like.

The principal object of this invention is to provide a stable dust-laying liquid composition resistant to removal from the soil by rain, and substantially without odor and color. Another object of this invention is to provide a stable dust-laying liquid composition which has high wetting ability in contact with soil. Other objects will be more readily apparent from the following detailed description of this invention.

Many compositions have been employed for laying dust on unpaved highways and railroad beds. The principal characteristics desired in such compositions are permanence of the dust-laying and binding action of the solution used and ease of wetting, or penetration of the composition into the soil. The most widely used compositions for this purpose have been aqueous solutions of calcium chloride and heavy petroleum oils of asphalt base. Solutions of calcium chloride are effective because of the hydroscopic property of the calcium chloride deposited in the soil. The chief disadvantage of calcium chloride, however, lies in the fact that it is readily soluble in water and is soon washed away by the rain. The crude asphaltic oils are more lasting but are undesirable because of their stickiness, odor and color and rather low wetting power. If the odor and color of such oils are removed by refining, their permanence is also destroyed. One type of dust preventative using a refined petroleum distillate has also been proposed by Hunter (U. S. Patent 2,122,524). The proposed composition consists of a refined petroleum distillate of 22 to 31° A. P. I. gravity containing a small quantity of hydrous degreas. This dust preventive composition is lasting, has good odor and color and has fair wetting properties, but is relatively unstable and tends to form separate layers upon standing before application to dust-forming surfaces.

In accordance with the present invention, it has been found that a stable dust-laying composition which combines good resistance to removal from soil by rain water, with good odor and color and good wetting properties can be provided by incorporating in a petroleum distillate of low viscosity and low volatility a small amount of a naphthenic acid compound with or without a wetting agent. The term "naphthenic

acid compound," as used herein and in the appended claims, includes crude and refined naphthenic acids and the metal naphthenate salts and mixtures containing them in predominating amounts.

For the base of the dust-laying composition of this invention, any relatively non-volatile or high-boiling petroleum distillate may be employed. However, it is advantageous to use a distillate oil fraction of moderately low viscosity. The distillate oil may be used in its unrefined state, or it may be refined. The degree of refining may be carried to any practical extent. A particularly satisfactory petroleum oil fraction for the purpose of this invention is a distillate of from 21 to 32° A. P. I. gravity having an SUS viscosity not under 55 seconds at 100° F. and possessing a minimum of petroleum odor.

With such a petroleum distillate there is admixed, according to this invention, a small amount of a naphthenic acid compound. Crude naphthenic acids are particularly suitable, although satisfactory results may be obtained with refined naphthenic acids and metal naphthenate salts. The amount of naphthenic acid compound incorporated in the petroleum distillate is such that no substantial separation of the naphthenic acid compound takes place on standing. In general, amounts corresponding to about 0.5 to 2.0 per cent by weight of the oil are used. When crude naphthenic acids are used in the oil, best results are obtained with concentrations of about 1 per cent by weight. Particularly good results are obtained with naphthenic acids having neutralization numbers on the order of about 200, but acids having lower or higher neutralization numbers, for example, from 100 to 270 may be used. Of the metal naphthenate salts, best results have been obtained with calcium naphthenate, tin naphthenate, zinc naphthenate and aluminum naphthenate when used in concentrations of about 0.5 per cent, although effective improvement can be obtained with amounts as low as 0.05 per cent by weight of the finished product.

These low percentages of metal naphthenates are particularly effective when used in admixture with naphthenic acids. It is desirable in general when using mixtures of metal naphthenates and naphthenic acids that less than 0.5 per cent by weight of the metal naphthenate be used.

The compositions thus produced comprising a light petroleum oil and 0.5 to 2 per cent of a naphthenic acid compound are effective dust-preventing agents, have good wetting power and stability and are resistant to removal from the

soil. However, the wetting properties of such a solution may be improved, if desired, by the additional incorporation of a minor amount of a wetting agent. Any suitable wetting agent may be used, and satisfactory results have been obtained with a variety of commercial wetting agents, such as "Tergitol" penetrants, "Dresinate," "Alkaterge-O" and the like. The Tergitol penetrants are, in general, aqueous solutions of the sodium salts of the sulfuric acid esters of higher alcohols usually containing 8 to 19 carbon atoms. Tergitol penetrant No. 4, for example, is an aqueous solution of the sodium sulfate derivative of 7-ethyl-2-methyl-4-undecanol; No. 7 is an aqueous solution of the sodium sulfate derivative of 3,9-diethyl-6-tridecanol; and No. 08 is an aqueous solution of the sodium sulfate derivative of 2-ethylhexanol. Dresinate is a well-known commercial wetting agent containing alpha-terpineol and sodium oleate. Alkaterge-O is also a well-known commercial wetting agent of the high molecular weight amine type compound.

If desired, a germicide may be added to the dust preventive composition of my invention. In such cases, dichloropentane, cresol, cresylic acid or the like may be added. In most cases, it has been found desirable that the amount of such germicide be not greater than about 0.2 per cent.

In general, the dust-laying compositions which have been found particularly suitable comprise a petroleum oil distillate of about 21 to 32° A. P. I. gravity in an amount corresponding to 97 to 99.5 per cent by weight; naphthenic acids in an amount corresponding to 0.5 to 1.75 per cent by weight; Tergitol penetrant No. 4 in an amount corresponding to 0.03 to 0.1 per cent by weight with or without up to 0.1 per cent of water and 0.2 per cent of a germicide. Particularly good results have been obtained with a composition containing 98.85 per cent of a petroleum distillate, 1 per cent of crude naphthenic acids, 0.05 per cent of Tergitol penetrant No. 4 and 0.1 per cent of water.

5 fication Board and the American Society for Testing Materials (D 332-31 T) with the exception that a standardized soil sample was used instead of a pigment. The procedure is as follows.

Take 1 gram, or any multiple thereof, of a pigment. Place the pigment upon a marble slab or glass plate and gradually add the oil, drop by drop, to the pigment, and after the addition of each drop thoroughly incorporate the oil with the pigment by the use of a stiff spatula. The test is completed when exactly enough oil has been incorporated with the pigment to produce a very stiff, putty-like paste which does not "break" or separate. A laboratory burette is used to measure the amount of oil incorporated into the pigment.

10 The standardized soil sample was prepared by grinding some typical top soil in a ball-mill until it passed through a No. 40 standard screen. The material was then dried in an oven at 250° F. for 6 hours.

15 20 25 In Table I there are shown the properties of the two base oils tested and the properties of the naphthenic acids used in compounding the dust-preventive compositions compared in the following example.

Table I

	Gravity, °A. P. I.	Viscosity, S. U. S. at 100° F.	Color N. P. A.	Neutralization No.	Pour point, °F.
Oil X-----	24.1	106.0	2	0.04	-45
Oil Y----- Naphthenic acids-----	22.3 14.1	105.0 767	5 -----	1.90 201.8	-40 -5

30 35 40 45 In Table II are shown the compositions tested and the wetting power of each as determined by the standard rub-out test. Then is shown also a comparison of the respective results showing the percentage increase in wetting power of oil Y and each of the compositions over oil X which had the lowest wetting power.

When the "Tergitol" was omitted from blend B, the increase in wetting power over oil X changed only from 34 to 33 per cent (blend C). When the naphthenic acids were omitted from blend B, however, the wetting power dropped from 34 to 21 per cent (blend D). Thus, the effect of naphthenic acids on the wetting power of an oil dust-preventing composition is quite pronounced.

Another blend, which was not shown in the above table, was made similar to blend A except that 2.0 per cent of naphthenic acids were used instead of 1 per cent. However, the larger amount of naphthenic acids gave only a slightly increased wetting power. The addition to the oils of more than 2 per cent of naphthenic acids had a detrimental effect upon the stability of the resulting compositions on standing.

EXAMPLE II

In this example there are illustrated the results obtained when using mixtures of naphthenic acids and metal naphthenates in dust-laying compositions prepared according to this invention. In Table II comparative results are shown between compositions prepared from oil X, above referred to in Example I, and this oil in combination with naphthenic acid alone, with tin naphthenate in concentrations of 0.5 and 0.05 per cent alone, and in admixture with naphthenic acids in amount corresponding to 1 per cent with 0.05 and 0.5 per cent of tin naphthenate.

Table III

	Oil X	Oil blends (make-up, percent by wt.)				
		1	2	3	4	5
Oil X	100	99.0	99.5	99.95	98.5	98.95
Naphthenic acids		1.0			1.0	1.00
Tin-naphthenate (12.2% Sn)			0.5	0.05	0.5	0.05
Amt. liquid to wet 100 gms. soil	34.4	27.5	28.2	28.5	27.4	26.8
Relative area wetted per unit vol. of oil to unit depth of soil	1.0	1.25	1.21	1.19	1.26	1.28
Per cent in wetting power over oil X		25	21	19	26	28

It will be observed from these results that combinations of the naphthenate with naphthenic acids are also effective for the purpose of this invention. In all of these tests the standard rub-out method referred to above in Example I was used.

The foregoing specification and description include the essential and distinctive thought of my invention, but it is to be distinctly understood that the same may be modified in various ways

and/or combined with various other details without affecting the peculiar results obtained, and without departing from the spirit of the invention or the scope of the appended claims in which I intend to claim all the patentable novelty inherent in my invention.

What I claim is:

1. A stable liquid dust-laying composition resistant to removal from soil by water and having high wetting power comprising 97.85 to 99.47 per cent by weight of a low viscosity, low volatility petroleum distillate oil of 21 to 32 degrees A. P. I. gravity, 0.5 to 1.75 per cent by weight of naphthenic acid, 0.03 to 0.1 per cent of a wetting agent consisting essentially of a sodium salt of a sulfonated higher alcohol, up to 0.1 per cent of water and up to 0.2 per cent of a germicide.
2. A stable liquid dust-laying composition resistant to removal from soil by water and having high wetting power comprising 98.85 per cent of a petroleum distillate oil of 21 to 32 degrees A. P. I. gravity, 1.0 per cent of naphthenic acid, 0.05 per cent of a wetting agent consisting essentially of the sodium sulfate derivative of 7-ethyl-2-methyl-4-undecanol and 0.1 per cent of water.
3. A stable liquid dust-laying composition resistant to removal from soil by water and having high wetting power comprising 98.85 per cent of a petroleum distillate oil of 21 to 32 degrees A. P. I. gravity, 1.0 per cent of naphthenic acid, 0.05 per cent of a wetting agent consisting essentially of

the sodium sulfate derivative of 3,9-diethyl-6-tridecanol.

4. A stable liquid dust-laying composition resistant to removal from soil by water and having high wetting power comprising 98.85 per cent of a petroleum distillate oil of 21 to 32 degrees A. P. I. gravity, 1.0 per cent of naphthenic acid, 0.05 per cent of a wetting agent consisting essentially of the sodium sulfate derivative of 2-ethylhexanol.

EDWARD R. BUTCHER.
